UNITED STATES PATENT OFFICE

169,873

LAWN SPRINKLER OR THE LIKE

Hugh W. Vogl, Wilmette, Ill.

Application January 15, 1953, Serial No. 23,152

Term of patent 14 years

(Cl. D91—1)

To all whom it may concern:

Be it known that I, Hugh W. Vogl, a citizen of the United States and residing in the city of Wilmette, in the county of Cook and State of Illinois, have invented a new, original, and ornamental Design for a Lawn Sprinkler or the like, of which the following is the specification, reference being had to the accompanying drawings, forming a part thereof.

On the drawings:

Fig. 1 is a side elevational view of my lawn sprinkler embodying my new design.

Fig. 2 is an elevation taken from the right of

Fig. 1. Fig. 3 is an elevation thereof looking at the left of Fig. 1.

Fig. 4 is a bottom view thereof. Fig. 5 is a top plan view of my lawn sprinkler.

I claim:

The ornamental design for a lawn sprinkler or the like, substantially as shown.

HUGH W. VOGL.
